CLAIM

The ornamental design for a cord clip, as shown and described.

DESCRIPTION

FIG. 1 is a front elevation view of a cord clip showing my new design in use with an electrical cord (shown in phantom);

FIG. 2 is a right side view thereof;

FIG. 3 is an inverted rear elevational view thereof;

FIG. 4 is a left view thereof;

FIG. 5 is a top view thereof; and,

FIG. 6 is a bottom view thereof.

The broken line showing of the cord is for illustrative purposes only and forms no part of the claimed design.
